UNITED STATES PATENT OFFICE.

PAUL HUDOWICZ, OF NEW YORK, N. Y.

SEPARABLE FASTENER.

1,216,571.

Specification of Letters Patent. Patented Feb. 20, 1917.

Application filed April 19, 1915. Serial No. 22,311.

To all whom it may concern:

Be it known that I, PAUL HUDOWICZ, a subject of the Emperor of Germany, and a resident of New York, in the county of New York and State of New York, have invented certain new and useful Improvements in Separable Fasteners, of which the following is a specification.

This invention relates to improvements in snap fasteners and in particular to the type used in engaging one portion of a shoe top with another.

The object of the invention is to provide a simple, yet highly efficient, securing means applicable broadly for many purposes and specially appropriate for use in connection with shoes in place of the hitherto common lacings or buttons.

It is a further object to provide such fastenings in forms rigidly attachable along the edges to be closed, the fastenings being easily and rapidly engaged, no hooks or other auxiliary appliance being required, and which can be disengaged with even greater despatch, when it is so desired.

These and other allied objects are attained by the novel construction and combination of parts hereinafter described and shown in the accompanying drawings, forming part of this specification, and in which:

Figure 1 is a perspective view of the upper part of a shoe, shown in an open position and indicating the application of the invention.

Fig. 2 is a fragmental sectional view, taken substantially on line 3—3 of Fig. 1.

Fig. 3 is a like sectional view, taken on line 4—4 of Fig. 1.

Fig. 4 is an enlarged perspective view of one of the fastener members, and,

Fig. 5 is a similar view of the other fastener member.

The essential elements of the invention are shown in detail in Figs. 5 and 6, the latter of which discloses a stiff, yet resilient, wire formed with end loops or eyes 10 and 11 respectively extended in opposite directions, by means of arms 12 and 13, from perpendicular side members 14 and 15, bent at right angles to the arms and joined by a reentrantly formed, open spring loop 16, the opening of which is of lesser magnitude than the loop itself.

This element is secured in such manner that the sides 14 and 15, together with the

loop 16, extend above the surface, (see Figs. 2 and 5) the loops 10 and 11 being rigidly engaged with the article by means of tubular rivets 17 and 18, the latter of which may be engaged below the outer covering and therefore obscured by it.

The other fastener element is also formed with loops or eyes 20 and 21, from which extend, in the same plane, arms 22 and 23, the same being bent toward each other at 24—25 and then joined by the open loop 26, constituting in effect a spring tongue.

This fastener element is preferably secured to the movable part of the article, either between the inner and outer portions, 70 or to the inside, by tubular rivets 28, in such manner that the rivets do not appear upon the outer or face surface of the top.

By reason of the distance between the securing loops and manner of fastening them 75 in place it will be evident that they rigidly hold the parts in a closed position up to the breaking point, and further, that the disposition of material in the first described element is such as to afford a desirable leverage to the vertical loop 16, enabling it to withstand considerable stress applied in the direction of the arms 12 and 13.

It is to be observed that the opening to the loop 16 is slightly less than the distance 85 between the points 24 and 25, so that when the movable element is firmly pressed upon the fixed element, these points will enter and become engaged in the loop 16, both elements being sufficiently resilient to permit of 90 this, forming a "snap" fastening of unusual merit.

It is also to be noted that the proportion of the parts are such that while in engagement they are substantially rigid and can not be 95 separated by a pull exerted in the direction of the length of the loop 26, yet by raising the movable part of the article, the parts can be readily separated.

To accomplish this purpose an elastic 100 gore 30 is secured at its sides and bottom to an inelastic border one side 31 of which is firmly engaged with the edge of the shoe top in such manner that the gore 30 acts as a cover strip over the front of the shoe, 105 while the other side 32 of the border is unattached, acting as a flap, to the edge of which is engaged the snap elements shown in Fig. 5.

Having thus described my invention, to- 110

gether with the manner of its application and use, what I claim as new and desire to secure by Letters Patent is:—

5 A shoe fastener comprising an eye member formed from a single strand of wire and bent to provide spaced attaching arms arranged in a direct line, arms extending inwardly to a point intermediate the attaching eyes, thence outwardly at right angles to 10 said arms, upwardly and inwardly to provide a reentrant spring loop, said loop being disposed at right angles to the arms of the attaching eyes, and a hook member formed from a single strand of wire and bent to 15 provide spaced attaching eyes, arms extend-

ing from said eyes and bent inwardly to form a neck portion and then outwardly to provide an elongated spring loop in line with the said arms, the neck portion being adapted to yieldingly engage within the said 20 reentrant spring loop for the purpose set forth.

Signed at New York, in the county of New York and State of New York this seventh day of April, A. D. 1915.

PAUL HUDOWICZ.
